UNITED STATES PATENT OFFICE

161,168

DESK OR SIMILAR ARTICLE

Jerome C. Eisenberg, West Orange, N. J.

Application July 30, 1949, Serial No. 4,216

Term of patent 14 years

(Cl. D33—7)

To all whom it may concern:

Be it known that I, Jerome C. Eisenberg, a citizen of the United States, residing in the town of West Orange, in the county of Essex and State of New Jersey, have invented a new, original, and ornamental Design for a Desk or Similar Article, of which the following is a specification, reference being had to the accompanying drawing, forming a part hereof.

I claim:

The ornamental design for a desk or similar article, as shown.

JEROME C. EISENBERG.
